KNIFE SHEATH HOLDER FOR A BELT

Frank J. Kamarad, Vallejo, Calif.

Application November 19, 1956, Serial No. 43,835

Term of patent 14 years

(Cl. D22—6)

Fig. 1 is a perspective view of a knife sheath holder for a belt showing my new design;

Fig. 2 is a top plan view thereof;

Fig. 3 is a front elevational view;

Fig. 4 is a rear elevational view; and

Fig. 5 is an end elevational view thereof looking at the right of Fig. 3.

The fragmentary broken line showing in Fig. 1 of the belt and knife sheath are for illustrative purposes only.

I claim:

The ornamental design for a knife sheath holder for a belt, substantially as shown and described.
